OPERATING TABLE ILLUMINATOR

Joseph Gelb, New York, N. Y.

Application October 17, 1931, Serial No. 569,413

11 Claims. (Cl. 240—1.4)

My present invention relates to illumination, and particularly is directed toward arrangements and apparatus which are designed to secure intense, uniform, and shadowless illumination by 5 artificial light over prescribed areas, which areas may encompass the entire floor area of rooms and similar enclosures, and/or working tables or benches therewithin. Illumination of this character is particularly desirable in the case of manual activities where intense illumination is desired and where shadows cast by the head, hands or instruments of the operator or operators must be avoided, as in the case of surgical operating tables, draftsman tables, medal chasers' and engravers' benches and game tables.

It is an object of the present invention to provide a novel illuminating arrangement which is adapted to yield a uniform, shadowless illumination over a prescribed area, whether such area 10 encompasses floor area of an entire room, or merely a much smaller horizontal area therewithin, which arrangement may be constructed of simple, readily available and inexpensive component parts, and readily assembled by unskilled labor, 15 and which does not require expensive and complicated lens or optical condenser combinations.

Another object is to provide an illuminating fixture which is adapted to make effective use of a relatively small light source to give rise to a 20 uniform and shadowless illumination, and which, although it depends for efficient operation upon precise and predetermined adjuxta position of the light source and the remainder of the structure, does not necessitate the utilization of difficult and 25 not readily manipulated adjusting arrangements.

Another object is to provide an illuminating fixture including lighting and reflecting elements which must be accurately positioned in respect to 30 each other to give the maximum efficiency, which elements are substantially automatically adjusted to said position of maximum efficiency upon assembly and installation without need for testing and measurement, and without likelihood of any change in the adjustment by loosening or shifting 35 of the various component parts, even though subjected to considerable shaking, jarring and rough handling.

Another object is to provide an illuminating fixture, involving the combination of a light source 40 and an annular reflecting arrangement, comprising a plurality of small, flat, inexpensive, individual reflector elements in a unitary, compact and substantially rigid assembly with an accurately predetermined arrangement of parts, from which 45 assembly one or more of said reflector elements

may be readily removed for repair or replacement, without returning the fixture to the manufacturer or dealer, and without the need for a complete disassembly and derangement and subsequent reassembly and readjustment.

Another object is to provide a completely enclosed illuminating fixture, particularly adapted to give the intense, uniform and shadowless illumination desired upon surgical operating tables, which enclosure is waterproof and also so shaped as to lend itself to being readily washed, and is also not only of pleasing appearance, but is free of any projections, shelves or ledges which would collect dirt and dust, with resultant possibility of infecting the field of operation.

Another object is to provide an illuminating arrangement, particularly adapted for surgical illumination and employing a relatively hot, high-power incandescent light source, which is so constructed and arranged that the heat generated therewithin will be readily disposed of without being in large part transmitted to the field of illumination and without risk of ignition of any of the volatile inflammable liquids and/or vapors customarily utilized by surgeons.

Other objects are in part obvious and in part 25 pointed out hereinafter.

In one embodiment of the present invention, an illuminating fixture may be constructed with an inner enclosure containing a light source, and having suitably positioned transparent walls, and with an outer enclosure containing an outwardly and downwardly sloping reflecting arrangement, annularly disposed around said source, for directing the light from said source downwardly and inwardly upon a predetermined area. The fixture may be so constructed and arranged that the light from the source, which may take the form of a high-power incandescent lamp, is reflected downwardly from a plurality of flat reflecting surfaces, either of polished metal or of mirror glass arranged as a continuous band, which band may conveniently take the form of frustrated pyramidal or conical sections, the apices of which are directed upwardly.

Although the fixture may be arranged so as to permit some of the light to pass directly down to the field of illumination, it is desired in a preferred embodiment to transmit all light to said field by a reflection from said frustrated annular reflecting surface. A light directing arrangement is preferably positioned around, and closely adjacent to the light source or incandescent lamp, and between said source and the annular reflector to cause transmission of the light radiated by the 55

lamp over its most effective zone to the reflecting surface, with assurance that such light will be transmitted downwardly and inwardly from all directions upon the field of illumination. The light directing arrangement between the lamp and the annular reflecting surface may take the form of a plurality of horizontally disposed shields, plates or disks, with which may be combined an annular lens or condenser, if desired. In one embodiment this arrangement completely shields the bottom of the light source and is so arranged about the maximum light transmitting zone, which for example may range from 45 degrees above the horizontal to 45 degrees below the horizontal, as to ensure transmission of the radiated light in said zone to the reflecting area in such a way that the desired dispersion and direction of the reflected light rays will be obtained. In order to assure proper relative positioning between the light source or incandescent lamp, the enclosing light directing arrangement and the annular reflecting surface, a stop or a stand is provided for the lamp, against or in which the lamp is positioned upon installation and replacement, the lamp being provided with a suitable extension which serves as a handle to enable correct positioning and also with a clamping arrangement to hold the lamp firmly in position. The reflecting surface, which may consist of a series of trapezoidal-shaped mirrors or polished metal plates, is preferably contained in a separate unit attached to the outer casing of the fixture. This unit may be provided with a holding frame with upper and lower retainer rings, circular or polygonal in shape, said rings consisting of a plurality of individually removable arcuate sections. If it is desired to remove or replace any one of the individual reflecting elements, the corresponding individual arcuate sections of the retainer rims may be removed, without need for dismantling or for disassembling the whole structure.

The bottom of the reflector, particularly when it is to be utilized for surgical purposes, may be covered by glass, which glass may be of heat and/or light absorbing qualities, and is protected from the heat of the light source by the above described shields enclosing the bottom of said source.

As an additional feature the inner enclosure of the fixture above described, may be associated with a blower arrangement so that air will be continuously circulated therethrough during use, carrying away the heat generated to a place distant from the field of illumination. This feature may be advantageously combined with an arrangement for preventing passage of any inflammable vapors, such as for example those of ether, chloroform, ethylene and so forth, to the inner enclosure where explosions or combustion may result, this being accomplished in one form causing the cooling current of air to first pass through a body of an absorbent, such as activated charcoal or silica gel enclosed between screens.

The arrangements of the present invention not only are adapted to illumination fixtures, but also are most suitably applicable to the uniform shadowless illumination of entire rooms and enclosures with white light, colored light or a variegated combination. In arrangements of this character, the light source may be preferably positioned centrally upon the ceiling of the room and may be enclosed by a horizontally spaced disk or plate arrangement of the character previously

described, with which may also be combined an annular lens or condenser. The outer edges of the ceiling are provided with a continuous series of reflecting mirrors or polished metal surfaces to receive the light in a substantial horizontal direction from the light source and then reflect it downwardly toward the floor to give the maximum field of illumination either upon the floor or at a desired distance thereabove. These reflector elements, which may take the form of rectangular surfaces, may be individually or collectively adjustable so as to have diverse reflecting angles and the light reflected therefrom and/or before incidence therewith may be caused to pass through colored transparent materials to give rise to variegated and artistic illuminating effects.

The invention is exemplified in the combination and arrangements of parts shown in the accompanying drawings and described in the following specification, and is more particularly pointed out in the appended claims.

Referring to the drawings,

Fig. 1 is a side view of an illuminating fixture suspended from the ceiling,

Fig. 2 is a side sectional view of the fixture upon an enlarged scale,

Fig. 3 is a fragmentary sectional view downwardly upon the line 3—3 of Fig. 2,

Fig. 4 is a bottom view of the reflector assembly of Figs. 1 and 2, removed from its casing,

Fig. 5 is an enlarged showing of a portion of Fig. 4,

Fig. 6 is a side section upon the line 6—6 of Fig. 4,

Fig. 7 is a sectional view upon an enlarged scale of the clamping arrangement upon the line 7—7 of Fig. 2,

Fig. 8 is a side sectional view upon enlarged scale of the absorbing arrangement upon the line 8—8 of Fig. 2,

Fig. 9 is a side view partly in section of a modification of the lamp housing of Figs. 1 and 2,

Fig. 10 is a modification showing diagrammatically in side sectional view an application to the general illumination of rooms,

Fig. 11 is a side view partly in section and upon enlarged scale of a condensing arrangement which may be used in Fig. 10,

Fig. 12 is an enlarged fragmentary showing of the reflector elements of Fig. 10, and

Fig. 13 is a side view upon the line 13—13 of Fig. 12 showing the adjusting arrangement.

In Figs. 1 and 2 the illuminating fixture A with the inner lamp enclosure B and the outer reflector containing enclosure C is suspended from the ceiling 20 by means of the cables 21 attached to the pins 22 on the exterior of the casing A. These cables lead to a suitable counter-weight and pulley arrangement 23 which may be of any suitable construction enabling ready adjustment of the fixture to any height. Leading down from the ceiling 20 are the lead-in wires 24, which pass through the tubular spindle 25 (see also Fig. 7), to the incandescent lamp 26 which is suitably attached to said spindle 25 by the bayonet or threaded connection 27. The upper inner portion of the outer enclosure C is provided with an opening to the edges of which is attached the domed cover 34 and the skirt 35 by the bolts 33, which skirt has inturned edges 36 supporting the chimney unit D and the deflector assembly F.

The chimney unit D has a cylindrical glass enclosure 38 firmly held between an annular flanged ring 39 and a bellied base plate 40. The annular retaining ring 39 and the base plate 40 are re-

tained in position by means of the rods 45 (see also Fig. 3) and the cylindrical spacers 46. These rods form part of the deflector assembly F and they carry in spaced relationship the annular disks 47, 48, 49 and 50 and the circular disks 51, 52 and 53. The annular disks encircle the lower part of the glass enclosure 38 and the disks 51, 52 and 53 are positioned below and enclose the base 40 of the inner enclosure 18. The upper 10 ends of the rods 45 are suspended from the in-turned lip 36 of the skirt 35.

The base 40 carries a series of symmetrically positioned posts 58, two of which in the embodiment shown carry the stand 59, which is provided with a circular opening 60 in which the bottom of the lamp 26 rests in its final position. In order to fix the lamp in this position, the spindle 25 (see also Fig. 7) is gripped by the split double tapered coupling sleeve 61. This 20 sleeve is in turn wedged between the nut 62 having a tapped socket 63 and the threaded nipple 64 projecting upwardly from the domed cover 34, the nut 62 and the nipple 64 being provided with tapered sockets 65 and 66 to receive the ends of 25 the said sleeve, the nut 62 has an expanded upper portion in the form of a knob or hub which may be easily and conveniently manipulated for adjustably connecting the skirt portion of the clamping nut to the associated upstanding and 30 threaded nipple of the dome.

From the top of the inner enclosure 19 by means of the downwardly extending brackets 71 is suspended the reflector assembly R. The top of the assembly is formed by the sector plates 35 72 (see also Figs. 4, 5 and 6), to the outer edges of which are attached the upper retainers 73 and the straps 74. The straps 74 carry the lower 40 retainers 75. The cover plate 72 and the retainers 73 and 75 form annular grooves around the top and bottom of the assembly in which are held the trapezoid-shaped reflectors 77, which are continuously arranged in close contact with each other around the entire circumference of the outer 45 enclosure C to form a frustrated many-side pyramidal section. The retainers 73 and 75 are attached together respectively, by the screws 78 and 79 to form continuous rings, said screws 78 also serving to attach the retainers 73 to the cover 72.

50 The outer casing or enclosure C extends downwardly and outwardly from the inner cover 34 by the curved surfaces 86 and 87, which lend an artistic appearance to the exterior of the fixture. An indentation 89 at the junction of said surfaces 86 and 87 serves as a stop for the top of the reflector assembly R. These surfaces 86 and 87 are respectively spaced from the roof 72 of the reflector assembly and from the annular reflecting zone 77 so that substantial air pockets 55 90 and 91 will be formed. They are of such shape that they may be readily wiped and/or washed.

60 Integrally attached to the lower edge of the curved surface 87 is the depending cylindrical skirt 92, which encircles and is bolted to the lower retaining ring 75. Depending from and bolted to the lower edge of the skirt 92 at 93 is the bottom assembly E. This assembly has a cylindrical wall 94 and a transparent bottom 70 95 which may be of glass, which bottom is clamped between the in-turned lip 96 of the cylindrical wall 94 and an L-shaped ring 97 bolted to said wall at 98, the gaskets 99 assuring a dust and water-tight connection.

75 In assembly and installation the reflector as-

sembly R may be placed within and attached to the outer casing C to which is then attached the skirt 35 of the inner enclosure B. The upper chimney retaining ring 39 is then placed upon the in-turned lip 36 and the chimney assembly F including the disks 47 to 53, the glass cylinder 38 and the base plate 40, all carried upon the rods 45 and properly spaced by the cylinders 46, is then attached to said ring 39 and said in-turned lip 36. The inner cover 34 carrying the spindle 25 and the lamp 26 is next placed in position. The expanded portion of the spindle 25 above the coupling nut 62 may be then used as a handle to place the incandescent lamp 26 into its proper position in the opening 60. The coupling nut 15 62 is then tightened, causing the split sleeve 61 to firmly grip the spindle in position. Finally, the outer enclosure C, the domed cover 34, and the skirt 35 are bolted together at 33, and the bottom cover assembly E is attached to the lower 20 edge of the skirt 92.

It will be noted that by this procedure the relative positions of the light and of the frustrated pyramidal or conical reflecting surface, will be definitely fixed in respect to each other. As a 25 result the light radiated over the most effective zone from the lamp, for example over a zone ranging from about 45 degrees above the horizontal to 45 degrees below the horizontal, will be picked up to a maximum extent by the reflector 30 zone and transmitted downwardly through the glass bottom 95 to the field of illumination. The annular disks 47, 48, 49 and 50 direct the light emitted from the lamp over this most efficient zone to the reflecting surface 77, and they may have 35 polished or light reflecting surfaces, as may also the bottom of the false ceiling 72 to assure more efficient transmission and diffusion of the light to the reflecting zone.

If the lamp is positioned above or below its indicated position the device will not operate at its maximum efficiency and a relatively smaller amount of the radiation of the lamp will be reflected downwardly in a satisfactory manner. It will be noted, however, that the exact positioning 45 of the lamp in respect to the reflecting zone is most readily obtained without the need for calibration, measurement or testing, substantially automatically upon assembly and installation when the lamp 26 is supported in its stand 50 58-59-60. The clamping of the spindle by the nut 62 and the sleeve 61 will assure that the lamp retain its position even after considerable usage and handling. To replace the lamp 26 it is only necessary to remove the cover 34, and if desired, 55 loosen the nut 62, reassembly of the new lamp in the predetermined position being readily accomplished as described.

The fixture will reflect the light downwardly in the form of a cone or pyramid and will give a zone 60 of maximum illumination at a place where most of the downwardly and inwardly reflected beams intersect. This zone of maximum illumination may be readily adjusted to coincide with a horizontal surface at any height within the room by 65 moving the fixture up and down, the supporting cords 21 and the counter-weight and pulley arrangement 23 retaining the fixture in any desired position.

Individual reflecting elements 77 after periods 70 of use, if of polished metal, may tarnish, or if of mirror glass, may crack, making it desirable to remove them. This may be done without deranging the whole fixture and without requiring readjustment of the lamp, by removing the bot- 75

tom cover assembly E and suitable individual ar-
cuate retainers 73 and 75, whereupon the partic-
ular reflecting elements 77 to be replaced may be
removed.

5 The air pockets 90 and 91 will maintain a more
uniform temperature adjacent the reflectors, and
particularly, if such reflectors are of mirror glass,
there will be less tendency for cracking and break-
age thereof due to sudden cooling of the exterior
10 casing C.

To prevent transmission of the heat rays to the
field of illumination, and/or to give desired col-
ored illumination, the glass chimney 38 and/or
15 the bottom glass 95 may be constructed of suit-
able absorbent glass, which will transmit only the
desirable rays from the lamp to the reflecting sur-
face and from the reflecting surface to the field of
illumination. The disks 51, 52 and 53 will also
20 serve to prevent excessive downward heat radia-
tion from the bottom 40 of the chimney as-
sembly B.

To remove additional heat generated upon oper-
ation of the device, a stream of air may be blown
25 into the enclosure B by the blower 101 and the
connecting flexible conduit 102. The air is then
removed by the flexible conduit 103 to some point
preferably exterior of the room. The flexible
tubes 102 and 103 are attached to the top of the
30 cover 34 by means of the sleeves 105 and 106.
These sleeves fit into the embossed openings 107
and 108, and are stopped against the top of the
cover 34 by the shoulders 109 and 110. The sleeve
105 is provided with a downward extension 111 so
35 that the air will be blown into the lower portion of
the enclosure B and around the lamp 26.

To prevent inflammable and explosive vapors,
such as of ether, chloroform and ethylene, which
40 are widely used by surgeons as anesthetics, from
flowing into the inner enclosure, it may be desir-
able in certain instances to place absorbent mate-
rial in the course of air flowing from the blower
101 to the enclosure B. This may be conveniently
45 accomplished by placing a cartridge 112 contain-
ing granules of silica gel, charcoal, or some other
absorbent material in the inlet sleeve 105, confined
between screens 113 and 114, which are held to-
gether by the inturned edges 115 of the metal cyl-
50 inder 116. The inlet portion of the sleeve 105 is
provided with a recess 117 to receive the cartridge
112 which is retained in place by the split ring 118.
Upon exhaustion the cartridge may be replaced by
removing the flexible hose 102 and then the split
ring 118.

In Fig. 9 is shown a modification in which the
55 base of the chimney is provided with a trans-
parent portion 119, which permits some of the
light from the incandescent light source to pass
directly downward to the field to be illuminated
without reflection. In this embodiment the par-
60 allel deflecting disk or shield arrangement F of
Fig. 2 has been omitted, but if desired, the annu-
lar disks 46, 47, 48, 49 and 50 may also be incor-
porated in this embodiment to direct the light
outwardly from the light source to the reflecting
65 band.

In applying the present invention to the illumi-
nation of rooms or other enclosures, (see Figs.
10 to 13), a light source 131, substantially of the
construction of Fig. 2 with the outer enclosure C
70 and the reflector assembly R omitted, may be sus-
pended from the ceiling 132, and completely en-
circling the room at the junction of said ceiling
and walls may be positioned a series of reflecting
mirrors or surfaces 134 which will function sub-
75 stantially the same as the reflecting elements 77 of

Fig. 2. It will be noted that these reflecting mir-
rors or surfaces are rectangular in shape, and
although they form a continuous band around the
light source, are not annularly disposed, but con-
form to the configuration of the room. If desired,
5 a lens or light condensing arrangement 135 (see
Fig. 11) may be utilized to replace, or in addition
to, the glass cylinder 38 of Fig. 2. The reflecting
plates 134 may all be adjustable as a unit (as
10 shown in Figs. 12 or 13) or they may be individu-
ally adjustable. In Figs. 12 and 13 the actuating
bar 136 is provided with a worm 137 which turns
the pinion 138, said pinion being clamped at 139
15 to a rod running along the back of and attached
to the mirrors or reflecting surfaces 134. By turn-
ing the actuating rod 136 any suitable angle of
reflection may be obtained and the zone of maxi-
mum illumination may be adjusted to any level
within the room.

If desired, part of the light reflected from the
surfaces 134 may be caused to pass through col-
ored transparent or translucent plates 140, which
may give a variegated or colored light effect to the
field of illumination. If desired the plates 140
20 may be extended across the entire ceiling of the
room to give a false ceiling and conceal the illumi-
nating arrangement. To increase or modify the
artistic lighting effects the glass cylinder 38 en-
closing the light source or the annular lens 135
25 (see Fig. 11), may also be colored or made of spe-
cial glass as shown.

The room as shown in Fig. 10 is specially con-
structed so that it will have retaining ledges 141
and 142 in which the reflecting surfaces or mir-
rors may be placed. If desired, however, by utilizing
30 a retainer structure similar to the assembly R
of Fig. 2 the illuminating arrangement of the
present invention may be applied to substantially
any room regardless of its size and construction,
one or more central lighting sources 131 being
35 utilized to give the desired degree and distribution
of illumination.

As many changes could be made in the above
construction, and many apparently widely differ-
ent embodiments of this invention could be de-
vised without departing from the scope thereof, it
is intended that all matter contained in the above
40 description or shown in the accompanying draw-
ings shall be interpreted as illustrative and not
in a limiting sense.

What I claim is:

1. A surgical illumination fixture comprising a
light source and a reflecting band encircling and
55 spaced therefrom, said reflecting band and said
light source being so correlated that maximum
efficiency is attained when they are in fixed rela-
tive positions, enclosures for said source and said
band being adapted to be opened respectively at
60 the top and bottom to receive the same, stops
within said enclosures to limit the insertion of
said source downwardly and said band upwardly,
whereupon said source and band will be in proper
position in respect to each other, and means to
65 attach said source and said band to said enclo-
sures upon stoppage.

2. A surgical illuminating fixture comprising an
outer cylindrical-like enclosure with opaque side
and top and a transparent bottom, said top being
formed of a plurality of downwardly curved sur-
faces and a central cylindrical enclosure extend-
70 ing through the top of the outer enclosure to ad-
jacent the transparent bottom thereof and hav-
ing a depending cylindrical portion with trans-
parent walls and a bottom supporting wall, a
stand in the lower part of said inner enclosure
75

including supporting legs resting on said bottom supporting wall, an incandescent lamp supported in said stand, a hollow spindle attached to said lamp containing the lead-in wires and extending 5 upwardly through the cover of said inner enclosure, a clamping arrangement to fix the spindle to said inner enclosure and the outer enclosure consisting in part of a plurality of trapezoidal reflecting surfaces placed side by side in a unitary 10 band and a series of individually removable arcuate retainers forming part of the assembly around the top and bottom of the band.

3. In a surgical illuminating device, the combination of, an outer casing including a band of reflectors, a housing disposed axially of said casing comprising a lamp member, a transparent element to shield said member, deflector means comprising a plurality of spaced annular plates encircling said element to deflect the light rays 20 from the member to the band of reflectors and means at one end of said element for seating a terminal of said member and position the latter at a predetermined elevation.

4. In a surgical illuminating device, the combination of an outer casing including a band of reflectors, a housing disposed axially of the casing and depending therefrom and comprising a lamp member, a transparent heat absorbing tubular element surrounding the member, spaced and 30 horizontally disposed light deflector means encircling said element, the housing having a stand on which a bulbous portion of the member is seated, a spindle connected to the member and extending through a part of the casing and clamping 35 means associated with the spindle and casing to hold the illuminating member in its seated position.

5. In an illuminating device, the combination of a stand, a lamp having a portion thereof seated 40 on the stand, a transparent cylindrical shield for the lamp, light deflector means comprising a plurality of spaced annular plates encircling said shield and light reflector means to provide shadowless illumination.

45 6. In an illuminating device, the combination of a stand having an opening, a lamp having a portion seated in the opening and guided by the sides thereof, a transparent heat absorbing tubular shield for the lamp, spaced and opaque light 50 deflector means encircling said shield, an enclosure surrounding the light deflector means and having a lower transparent but heat absorbing wall, and reflector means to provide a shadowless illumination.

55 7. In a surgical lighting device, the combination with a principal electrical light source compris-

ing an incandescent lamp of a system of deflecting mirrors adapted to reflect light rays on to a surface so situated relative to said light source as to receive shadowless illumination, light deflector spaced plates encircling said source and interposed intermediate the latter and said system and means to adjustably sustain said lamp fixedly with respect to said system comprising a member extending from said lamp, a cooperating nut having an expanded manipulating portion, a nipple 10 threadably engageable with the nut and tapered coupling sleeve seated between said nipple and member and adapted to be contracted or expanded upon the actuation of said manipulating portion.

15 8. In an illuminating device, the combination of, an outer casing including an annular band reflector, a housing disposed axially of the casing and depending therefrom, a lamp disposed axially of said housing, a transparent cylindrical 20 shield surrounding said lamp, a stand having an opening for seating a lower portion of said lamp, a plurality of spaced annular light deflecting plates surrounding said shield and a transparent body secured at the lower end of said casing.

25 9. In combination, a stand, a lamp having a portion seated on said stand, a transparent tubular shield for said lamp, a plurality of spaced annular light deflecting members encircling said shield, an enclosure surrounding said members 30 and having a transparent closure disposed below said members and reflector means carried by said enclosure to provide shadowless illumination.

35 10. In combination, a stand, a lamp having a portion seated on said stand, a transparent tubular shield for said lamp, a plurality of spaced annular light deflecting members encircling said shield, an enclosure surrounding said members and having a transparent closure disposed below 40 said members, reflector means removably carried by said closure to provide shadowless illumination, and means for holding said lamp in its seated position.

45 11. In combination, a stand, a lamp having a portion seated on said stand, a transparent tubular shield for said lamp, a plurality of spaced annular light deflecting members encircling said shield, an enclosure surrounding said members and having a transparent closure, a band of reflector elements to provide shadowless illumination and a frame carried by said enclosure for detachably supporting several groups of said light reflecting 50 elements.

JOSEPH GELEB. 55
